UNITED STATES PATENT OFFICE

152,674

DESIGN FOR A MARINE VESSEL

William Costa, San Diego, Calif.

Application July 16, 1947, Serial No. 140,320

Term of patent 14 years

(Cl. D71—1)

To all whom it may concern:

Be it known that I, William Costa, a citizen of the United States, and a resident of San Diego, in the county of San Diego and State of California, have invented a new, original, and ornamental Design for a Marine Vessel, of which the following is a specification, reference being had to the accompanying drawings, forming part thereof, wherein

Figure 1 is a perspective side and top view of a marine vessel embodying my new design.

Figure 2 is a prow elevation of the vessel.

Figure 3 is a side and bottom perspective view of the vessel.

Figure 4 is a stern elevation of the vessel.

I claim:

The ornamental design for a marine vessel, substantially as shown.

WILLIAM COSTA.
